MULTICOLUMN SELECTOR

Ernest Rose, Washington, D. C., assignor to International Business Machines Corporation, New York, N. Y., a corporation of New York

Application June 4, 1935, Serial No. 24,814

6 Claims. (Cl. 209—110)

The present invention relates to record controlled machines in general and, in particular, to machines for sorting accounting and statistical records.

5 The object of the invention is to provide means for controlling record controlled machines to the end that the parts of the machine are actuated the fewest number of times in order to reduce wear and noise to a minimum.

10 An object is to provide an improved multi-column selector which so controls the machine that the machine operations required to handle a batch of records is the least number possible.

Another object is to provide an improved multi-column selector for sorting machines which causes the pocket selecting mechanism to be actuated only when a record is not to be rejected but is to be guided to a predetermined pocket.

15 A specific object is to improve the sorting machine described in Letters Patent No. 1,933,357, granted to Weinlich and Kolm, to reduce wear and noise.

20 Various other objects, advantages and features of the invention will be specifically mentioned 25 in the following description and claims or will be obvious from a study of the description, claims, and drawing.

The drawing consists of a wiring diagram of a 25 sorting machine constructed in accordance with 30 the above patent as modified and improved by the invention described hereinafter.

The numeral 1 designates generally a multi-column selector commutator like the one described in the above patent. When this commutator is properly set up to represent a given number punched in the cards which are to be selected, the commutator will be non-current conducting whenever a card so punched passes between the contact roll 2 and the analyzing brushes 40 3 associated with the commutator 1.

If a card is not so punched, however, a circuit will be set up through one or more of the segments of the commutator and one or more of the brushes 3 as described in the patent.

45 15 The numerals 4 and 5 designate the usual single column selector, of which 4 is a multi-segment commutator while 5 is a holding segment. This commutator is described in detail in Patent No. 1,741,985. In the present case only 50 20 the holding segment 5 need be considered and it will be understood that switch S1 is in its dotted position to condition the machine for multi-column selecting operations, thereby disconnecting commutator 4 from the contact roll 2.

55 25 When normal sorting operations are carried

out, switch S1 is placed in its solid line position, thereby connecting the contact roll 2 to commutator 4 through safety contacts 6 and the contact roll brush 1. The regular single column sorting brush 8 then replaces the brushes 3 in the usual brush holder. A switch S2 is closed to connect the usual brush relay R1 and sorting magnet SM in a series circuit extending from line wire W1, commutator 4, switch S1, contacts 6, brush 1, contact roll 2, brush 8, relay R1, switch S2, and sorting magnet SM, to line wire W2. This circuit is established whenever brush 8 encounters a hole of any given value in the column of the card traversed by said brush and causes magnet SM to be energized at the proper point 15 in the cycle to cause the card to be conveyed to the pocket of corresponding value.

According to this invention, a second relay R2, a commutator 9, and two additional switches S3, S4 are provided to control the machine in co-operation with the multi-column selector commutator 1. The commutator 9 has a segment of conducting material which is continuous with respect to one of its brushes 10 and discontinuous with respect to the other brush 11. This discontinuous portion is of a length sufficient to electrically connect brushes 10, 11, momentarily at the "12" position, that is, at the point in the cycle where brushes 3 cooperate with the "12" index-point positions of the card. Switch S4, 30 commutator 9, and the contacts of relay R2 are included in a series circuit extending from line wire W1, the commutator 5, contacts of relay R2, brushes 10, commutator 9, brush 11, switch S4, and sorting magnet SM, to line wire W2. 35 With switch S4 closed for multi-column selecting operations, the above described circuit is established at the "12" position of each cycle by commutator 9 and has a tendency to cause all cards to be sorted into the "12" pocket. When the 40 machine is to operate under control of commutator 1, switches S3, S4 are closed and switch S2 opened, and switch S1, as previously stated, placed in its dotted line position.

When the brushes 3 sense the holes in cards 45 designating the given number set up on commutator 1, which cards bearing the given number are to be segregated from all others, no circuit is set up through commutator 1 as explained in the Weinlich patent, relay R2 is not energized, and 50 the commutator 9 becomes effective to close the circuit through sorting magnet SM, thereby flexing the sorting blades at the proper point to cause the cards bearing the given number to drop into the "12" pocket.

On the other hand, if the holes in the cards designate some number other than the given number, a circuit will be established from line wire W1, safety contacts 12, through commutator 1, brushes 3, contact roll 2, brush 1, contacts 6, switch S1, relay R2, and switch S3, to line wire W2. Relay R2 opens its contacts and prevents commutator 9 from closing the circuit through sorting magnet SM. As a result all cards 10 not punched with the given number will be conveyed to the reject pocket instead of being conveyed to the "12" pocket.

In the machine described in the patent all cards bearing the given number are rejected 15 while all others are diverted to the "12" pocket. This mode of operation has been found to cause unnecessary wear on the machine and excessive noise particularly where the cards to be selected comprise only a small proportion of the entire 20 batch. Since the sorting blades and parts directly actuated by the magnet SM are the most delicate part of the mechanism of the machine, it is obvious that to operate this magnet for each card which is to be rejected results in unnecessary wear.

As an illustration, the searching of finger print records of a large criminal records office, wherein there are several million finger print record sheets, is controlled by selective sorting of 30 perforated record cards each of which represents a single finger print record sheet. The principal problem in this office, as in similar finger print bureaus throughout the country, is to find, if possible, the finger print record sheets which bear 35 the closest resemblance to the finger prints of a suspected person, an unidentified body, or prints obtained at the scene of a crime or on articles handled by a criminal.

The searching procedure is simplified to some 40 extent by the method of classification but, nevertheless, several hundred thousand records may have to be searched in order to locate the few records bearing the closest resemblance to the ones under consideration. This searching procedure is now very much shortened by using a 45 sorting machine equipped with a multi-column selector like the one disclosed in the patent. Nevertheless, many thousands of cards must be passed through the machine to select the bare 50 handful of cards corresponding to the desired finger print record sheets. If, for instance, only 1% of the records searched are likely to be found of interest, the sorting magnet must operate 99 times for each hundred cards merely to select 55 one card. In a batch of 50,000 cards, the sorting magnet would have to operate the guide blades 49,500 times to select only 500 cards. As the guide blades are of spring-tempered flexible steel, as shown in the patent, it is obvious that the blades 60 will be flexed so frequently as to rapidly become fatigued and lose their temper much sooner than would be the case under normal conditions of operation. These blades are fairly expensive since there are twelve of them ranging in length from 65 a few inches to several feet.

Relays R1, R2, on the other hand, cost only a few cents to make and can be replaced in a few minutes, whereas to replace the guide blades entails partly dismantling the machine and readjustment requiring an appreciable amount of time.

When the machine is constructed in accordance with the present invention, the magnet SM is operated and hence the blades are flexed only 75 for a few wanted cards and the only serious wear

on the machine is that due to the abrasive action of the cards on the turned up ends of the blades. The effect of flexure fatigue on the blades of a machine constructed in accordance with this invention is negligible and, since the blades are of tempered steel, the abrasive action of the cards on the blades is not great as the blades resist this form of wear better than flexure fatigue.

While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described, a sorting circuit including a sorting magnet, means normally tending to close said circuit to effect a predetermined distribution of records, a multi-column selector settable to represent cards to be selected, and means controlled by said selector for 25 interrupting said circuit for cards other than those to be selected.

2. In a machine of the class described, sorting mechanism including a sorting magnet for operating said mechanism, means to periodically energize the sorting magnet to normally cause records to be conveyed to a given pocket, a multi-column selector settable to represent cards to be selected, and means controlled by said selector for preventing energization of the sorting magnet for 35 records other than the ones to be selected.

3. In a sorting machine, a card analyzing device; a multi-column selector connected to said device and settable in accordance with predetermined numbers to select cards designated with 40 such numbers, said selector being operative to break the circuit through the analyzing device only when the designations in the records agree with the number set up on said selector; a sorting magnet, means tending to periodically energize the sorting magnet, and means in circuit with the selector device for preventing the first named means from taking effect when the numbers designated on the records disagree with the number set up on the selector. 50

4. In a machine of the class described wherein the sorting mechanism includes a series of spring guide blades flexed under control of a sorting magnet, a sorting circuit including said magnet and also means to energize the sorting magnet at 55 a predetermined point in each cycle whereby to operate said blades to cause a card to be conveyed to a predetermined point, a relay for interrupting said circuit, and a multi-column selector settable in accordance with predetermined 60 numbers with which some of the cards are designated and operative to energize said relay when numbers on the cards disagree with the number set up on the selector. 65

5. In a sorting machine wherein sorting is effected by spring guide blades which are selectively flexed under control of a sorting magnet, the combination with said magnet, of a circuit for controlling said magnet with means to periodically close said circuit whereby to cause regular flexing of the blades to guide cards to a given destination, means operable to interrupt said circuit to prevent flexure of the blades, and a multi-column selector for controlling the interrupting means, said selector being settable in accordance 70 75

- with a given number with which certain cards are designated and operating the interrupting means only when the numbers in the cards fail to agree with the number set up on the selector 5 whereby said blades are flexed only when the cards are designated with the predetermined number.
6. In a sorting machine wherein records are sorted by selectively flexing a series of flexible 10 guide blades which determine the distribution of the records, means normally tending to cause flexure of the blades at regular intervals to pro-

duce a fixed distribution of the records, means operable to prevent flexure of the blades, and a multi-column selector settable in accordance with predetermined numbers with which certain of the records are designated, said selector operating the preventing means to prevent flexure of the guide blades whenever the numbers on the cards disagree with a number set up on the selector whereby all the cards not designated with said number are rejected. 5
